THREAD ADVANCING REEL

Seddon C. Nelson, Front Royal, Va., assignor to
American Viscose Corporation, Wilmington,
Del., a corporation of Delaware

Application December 20, 1947, Serial No. 792,957

12 Claims. (Cl. 28—71.6)

1

This invention relates to thread advancing reels for forming a thread store comprising a plurality of spaced turns of thread that are continually advanced in an axial direction along the periphery of the reel. These reels may be used for the purpose of storing the thread or the thread may be subjected to fluid treatment or dried on the reels in the manner and for the purpose conventional in the art.

In thread advancing reels shown in the prior art, the reels often comprised a large number of parts and elaborate means were required for supporting the various parts in operable relation. These reels were expensive to construct and difficult to maintain.

This invention has for its principal object to provide forms of thread advancing reels that overcome disadvantages and objections found in reels of the prior art.

Another object of the invention is to provide unitary forms of thread advancing reels of simplified construction that will be economical to manufacture and maintain during operation.

These and other objects and advantages of the invention will be apparent from the following description and accompanying drawings.

In the drawings:

Figure 1 is a vertical sectional view of a form of thread advancing reel embodying this invention.

Figure 2 is a transverse sectional view of the form of thread advancing reel shown in Figure 1, the section being taken on the line A—A in Figure 1.

Figure 3 is a sectional view of a portion of the form of thread advancing reel shown in Figures 1 and 2, the section being taken on the line B—B in Figure 1.

Figure 4 is a vertical sectional view of another form of thread advancing reel embodying this invention.

This invention may be used for handling yarn, filaments, tow, bands, ribbons, and the like as well as thread and the term thread as used above and hereinafter is intended to be inclusive.

The invention in general comprises two circular cage-like members each comprising a plurality or set of longitudinally extending circumferentially spaced thread supporting bars that are mounted to rotate about spaced apart or eccentric axes positioned within the periphery of each of the cage-like members. The bars making up one cage-like member are positioned between the bars of the other cage-like member. Means are provided for positively moving the

2

bars of one of the cage-like members relative to the bars of the other cage-like member in a direction having at least a component in an axial direction to advance in an axial direction turns of thread wound on the reel. One of the cage-like members is mounted for rotation on means that are separate from the other cage-like member and the means on which the other cage-like member is mounted, and the means on which the first cage-like member is mounted are maintained stationary during the operation of the reel by the inertia of the means and in addition in certain cases by the force of gravity.

Referring to Figures 1 and 2 of the drawing in which is shown an embodiment of the invention having two cage-like members mounted to rotate about parallel eccentric axes with the circularly spaced thread supporting bars of one of the cage-like members fixed and restrained from movement in an axial direction and the circularly spaced thread supporting bars of the other cage-like member positively movable in an axial direction, reference character 1 indicates generally the cylindrical cage-like member having the fixed thread supporting bars 2. The thread supporting bars 2 extend axially and are attached in parallel relation and uniformly spaced apart circumferentially to the circular end flange members 3 and 4 that are centrally fixed to the rotatable shaft 5. An annular groove 6 is formed in the end flange 3 concentric with the axis of the shaft. One end portion of the thread supporting bars extends into the groove where they are fixed and the thread supporting bars are secured adjacent the other end to the end flange 4 by separate clamping and attaching members 7 for each bar. A gear 8 by which the reel is driven is fixed to the shaft. The cage member 1 is rotatably supported adjacent each end in bearings in the standards 9 and 10. Bearing means 11 and 12 are positioned between the shaft and the standards and sealing means 13 and 14 are positioned between the hubs 15 and 16 on the end flanges and the standards into which they extend. While supporting means for each end of the reel have been shown and described, if desired, particularly in the case of reels of short length, the standard 10 at the end of the reel opposite the driven end may be omitted.

Reference character 20 indicates generally the cylindrical cage-like member having the movable thread supporting bars 21 which are positioned between the fixed thread supporting bars 2 and parallel thereto. The movable bars are mounted to rotate about an axis that is parallel to but

eccentric or spaced from the axis of the shaft about which the fixed thread supporting bars rotate. The means on which the cage-like member 20 having the movable thread supporting bars is mounted comprises, positioned between the end flanges and separate and spaced therefrom, an axially extending tubular member 23 having a hub-like member 24 fixed to or formed integral with the tubular member at each end. The shaft extends through the tubular member and the hub members and is journaled in the tubular member in the ball or roller bearings 25 the outer races of which are fixed to the tubular member and the inner races are fixed to the shaft. The tubular member and the hub-like members in effect float on the shaft out of engagement with any part of the cage-like member 1. The hub members 24 are each formed with a portion 35 having a cylindrical outer surface or other surface of revolution, the axes of which are eccentric to and canted transversely with respect to the axis of the shaft, each in the same direction. Roller or ball bearing members 26 having inner and outer races are mounted on the portions of the hub members having the cylindrical or other surface of revolution. Circular skew disk-like members 26a are centrally mounted on each of the bearing members 26 and are clamped to the outer races by the annular clamping members 27 bolted to the skew disks. Due to the canting of the axes of the surfaces on the hub members on which the skew disks are rotatably mounted, the skew disks rotate in planes that are canted or inclined in the same direction from planes perpendicular to the axis of the shaft.

The reel is provided with a tubular sealing member 28 of flexible rubber, plastic, or the like material to prevent the entrance of fluids to the inner parts of the reel. The tubular seal surrounds the skew disks and is fixed at its ends by clamping means 30 to the shoulders 29 on the end flanges.

The movable thread supporting bars are attached to the skew disk members by the bolts or screws 31 that extend through the resilient yieldable cushioning means 32 of rubber or the like that are positioned in bored out portions in the bars located in the region the bars are attached to the skew disks. A cushioning means is held in the bar by the annular ridge or shoulder 34 that extends into an annular groove formed in the cushioning means. To assist in maintaining the tubular member 23 and the hub members 24 stationary during the rotation of the reel, the lower portion of the tubular member is weighted by the pendulum-like weight member 33 that is rigidly attached thereto.

In the operation of this embodiment of the invention, the cage member comprising the fixed bars is rotated with the shaft about the axis of the shaft by means of the gear 8 meshing with a drive gear that is not shown. The cage member having the movable bars is rotated by the other cage member through the tubular sealing means and by at least one of the fixed bars engaging an adjacent movable bar. The movable bars rotate about an axis that is eccentric and parallel to the axis of the shaft and due to the skew disks rotating in planes that are inclined from a right angle or askew with respect to the axis of the shaft the bars attached to the skew disks are positively moved in an axial direction, the cushioning members accommodating the slight movement between the bars and

the skew disks. The inclination of the skew disks is so related to the eccentricity of the disks with respect to the axis of the shaft that the movable bars are moved in the direction it is desired to advance the turns of the thread when the movable bars are outside the periphery of the fixed bars comprising the other cage member and the movable bars are retracted or moved in the opposite direction when the movable bars are within the periphery of the fixed bars comprising the other cage member.

While the cage members in this embodiment of the invention are shown as cylindrical it is to be understood that where it is desired to stretch or relax the thread on the reel, the cage members may be of frusto conical form.

Referring to Figure 4 of the drawing in which is shown another embodiment of the invention having two cylindrical cage-like members mounted to rotate about inclined eccentric axes with the circularly spaced thread supporting bars in each cage member fixed to an end flange, reference character 40 indicates generally a cylindrical cage-like member having axially extending thread supporting bars 41. The thread supporting bars 41 are positioned in parallel relation and uniformly spaced apart circumferentially, and are attached to an end flange 42 that has a hub portion 43 keyed to the shaft 44. The shaft is journaled in the standard 45. A gear 46 by which the reel may be driven is fixed to the shaft.

Reference character 47 indicates generally the other cylindrical cage-like member having the thread supporting bars 48 positioned between the thread supporting bars of the cage-like member 40. The thread supporting bars 48 extend axially in parallel relation and uniformly spaced apart circumferentially and are attached to the end flange 49 that has a central hub portion 50 mounted to rotate about an axis that is eccentric to and is canted transversely with respect to the axis of the shaft. The means on which the cage-like member 47 is mounted comprises the axially extending tubular member 51 having fixed thereto or formed integral therewith the hub member 52. The shaft extends through the tubular member and the hub member and is journaled in the tubular member in the ball or roller bearings 53 the outer races of which are fixed to the tubular member and the inner races are fixed to the shaft. The tubular member and the hub member in effect float on the shaft out of engagement with any part of the cage-like member 40. The hub member 52 is formed with a portion 54 having a cylindrical outer surface or other surface of revolution the axis of which is eccentric to and canted transversely with respect to the axis of the shaft. The cage member 47 is rotatably mounted on the portion 54 of the hub having the surface of revolution to rotate relative to the tubular member and the hub member and is maintained in position by the washer 57 and ring member 58 fixed to the shaft.

To assist in maintaining the tubular member 51 and the hub member 52 stationary during the rotation of the reel, the lower portion of the tubular member is weighted by the pendulum-like depending weight 55 that is rigidly attached thereto.

In the operation of the embodiment of the invention shown in Figure 4, the cage member 40 is rotated with the shaft 44 by means of the gear 46 meshing with a drive gear that is not shown. The cage member 47 is rotated by at least one

thread supporting bar of the cage-like member 40 engaging a thread supporting bar of the cage-like member 41. The cage-like member 41 rotates about the portion 54 of the hub member that is fixed to the stationary tubular means 51. The axis of the portion 54 is eccentric to and canted transversely with respect to the axis of the shaft so that the end flange 49 rotates in a plane that is inclined from a plane at right angles to the axis of the shaft. The tubular member 51 on which the cage member 41 is mounted is entirely separate and apart from any part of the other cage member 40 and remains stationary during the operation of the reel. The cage member 41 in rotating about its axis which is inclinde to that of the cage member 40 moves the thread supporting bars 48 relative to the thread supporting bars 41 in a direction that has a component extending longitudinally of the reel to advance in a longitudinal direction turns of thread wound thereon. Due to the relation of the eccentricity and the cant or inclination of the cage-like members the thread supporting bars 48 are moved in a direction having a component in the direction it is desired to advance the thread when they are in contact with the thread and those bars are moved back in the opposite direction when they are out of contact with the thread.

Magnetic means may be employed in this invention for maintaining stationary, the stationary means on which one of the cage-like members is mounted. The weight member may comprise a magnet or be of magnetic material and a magnet or member of magnetic material, depending on the nature of the weight member, is positioned adjacent the reel in position to set up a magnetic attractive force between the weight member and the magnet or magnetic material positioned adjacent the reel.

While preferred embodiments of the invention have been shown and described, it is to be understood that this is by way of illustration and that changes and variations may be made without departing from the spirit and scope of the invention as defined in the appended claims.

I claim:

1. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel, separate means on which the cage-like members are mounted for rotation about axes that are eccentric to each other, means for moving the thread supporting bars of one cage-like member in a longitudinal direction relative to the thread supporting bars of the other cage-like member, the means on which one of the cage-like members is mounted being floatingly mounted on a fixed axis and spaced from and independent of the reel supporting means and means for holding the floatingly mounted means stationary.

2. A thread advancing reel comprising two cylindrical cage-like members each having a plurality of longitudinally extending circumferentially spaced thread supporting bars with the thread supporting bars of one cage-like member positioned between the thread supporting bars of the other cage-like member, separate means on which the cage-like members are mounted for rotation about axes that are eccentric to each

other, means for moving the thread supporting bars of one cage-like member in a longitudinal direction relative to the thread supporting bars of the other cage-like member, a weight member attached to the means on which one of the cage-like members is mounted to maintain the means stationary during the operation of the reel.

3. A thread advancing reel comprising two cylindrical cage-like members each having a plurality of longitudinally extending circumferentially spaced thread supporting bars with the thread supporting bars of one cage-like member positioned between the thread supporting bars of the other cage-like member, separate means on which the cage-like members are mounted for rotation about axes that are eccentric to each other, means for moving the thread supporting bars of one cage-like member in a longitudinal direction relative to the thread supporting bars of the other cage-like member, a weight-like member attached to and depending from the means on which one of the cage-like members is mounted to maintain the means stationary.

4. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel, separate means on which the cage-like members are mounted for rotation about axes that are eccentric to each other, means for moving the thread supporting bars of one cage-like member in a longitudinal direction relative to the thread supporting bars of the other cage-like member, one of said means on which one of said cage-like members is mounted comprising a shaft and the other of said means on which the other cage-like member is mounted comprising a stationary member through which the shaft extends floatingly mounted on the shaft, said floatingly mounted member being spaced longitudinally of the reel from the reel supporting means, and means for holding the floatingly mounted member stationary.

5. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel, separate means on which the cage-like members are mounted for rotation about axes that are eccentric to each other, one of said means comprising a shaft on which one of said cage-like members is mounted and the other of said means comprising a member through which said shaft extends floatingly mounted on the shaft, said floatingly mounted member being spaced longitudinally of the reel from the reel supporting means and having a portion that is eccentric and askew to the axis of said shaft and on which the other cage-like member is mounted.

6. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary means for supporting the reel, separate means on which the cage-like members are mounted for rotation

about axes that are eccentric to each other, one of said means comprising a rotatable shaft to which one of said cage-like members is fixed and the other of said means comprising a stationary means through which said shaft extends that is separate from said cage-like member, said stationary means being spaced longitudinally of the reel from the reel supporting means and independent thereof and having a portion formed with a surface of revolution the axis of which is canted with respect to the axis of the shaft and on which the other cage-like member is rotatably mounted.

7. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel, separate means on which the cage-like members are mounted for rotation about axes that are eccentric to each other, one of said means comprising a shaft on which is mounted a disk-like member to which the bars of one of the cage-like members are attached, the other of said means comprising a member through which the shaft extends floatingly mounted on the shaft, said member being spaced longitudinally of the reel from the reel supporting means with the disk-like member positioned between the reel supporting means and the member, the member having a portion that is eccentric and askew to the axis of said shaft and on which the other cage-like member is mounted.

8. A thread advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel, separate means on which the cage-like members are mounted for rotation about axes that are eccentric to each other, one of said means comprising a shaft on which one of said cage-like members is mounted and the other of said means comprising a member through which said shaft extends floatingly mounted on the shaft, said floatingly mounted member being spaced longitudinally of the reel from the reel supporting means and having spaced portions that are eccentric and askew to the axis of said shaft and on which the other cage-like member is mounted.

9. A thread advancing reel comprising two cylindrical cage-like members each having a plurality of longitudinally extending circumferentially spaced thread supporting bars with the thread supporting bars of one cage-like member positioned between the thread supporting bars of the other cage-like member, separate means on which the cage-like members are mounted for rotation about axes that are eccentric to each other, one of said means comprising a shaft on which one of said cage-like members is mounted and the other of said means comprising a stationary means through which said shaft extends, said stationary means having a portion that is eccentric and askew to the axis of said shaft and on which the other cage-like member is mounted, and weight means attached to said stationary means for maintaining

said stationary means stationary during operation of the reel.

10. A thread advancing reel comprising two cylindrical cage-like members each having a plurality of longitudinally extending circumferentially spaced thread supporting bars with the thread supporting bars of one cage-like member positioned between the thread supporting bars of the other cage-like member, separate means on which the cage-like members are mounted for rotation about axes that are eccentric to each other, one of said means comprising a shaft on which one of said cage-like members is mounted and the other of said means comprising a stationary means through which said shaft extends, said stationary means having a portion that is eccentric and askew to the axis of said shaft and on which the other cage-like member is mounted, and weight means attached to and depending from said stationary means for maintaining said stationary means stationary during operation of the reel.

11. A thread advancing reel comprising two cylindrical cage-like members each having a plurality of longitudinally extending circumferentially spaced thread supporting bars with the thread supporting bars of one cage-like member positioned between the thread supporting bars of the other cage-like member, separate means on which the cage-like members are mounted for rotation about axes that are eccentric to each other, one of said means comprising a shaft on which one of said cage-like members is mounted and the other of said means comprising a stationary means freely supported on said shaft, said stationary means having a portion that is eccentric and askew to the axis of said shaft and on which the other cage-like member is mounted, and depending weight means attached to said stationary means for maintaining said stationary means stationary during operation of the reel.

12. A threaded advancing reel comprising two cylindrical cage-like members each having a plurality of longitudinally extending circumferentially spaced thread supporting bars with the thread supporting bars of one cage-like member positioned between the thread supporting bars of the other cage-like member, stationary supporting means for the reel positioned adjacent one end of the reel, separate means on which the cage-like members are mounted for rotation about axes that are eccentric to each other, one of said means comprising a shaft having a free end on which shaft one of said cage-like members is mounted and the other of said means comprising a member through which said shaft extends floatingly mounted on the shaft, said member being spaced longitudinally of the reel from the reel supporting means and having a portion adjacent the free end of the shaft that is eccentric and askew to the axis of said shaft and on which the other cage-like member is mounted.

SEDDON C. NELSON.
